United States Patent Office

Des. 225,302

Patented Dec. 5, 1972

225,302

CABINET HARDWARE

Raymond U. H. Tegner, Rockford, Ill., assignor to
Amerock Corporation, Rockford, Ill.

Filed July 1, 1971, Ser. No. 159,879

Term of patent 14 years

Int. Cl. D8—07

U.S. Cl. D8—166

FIG. 1.

FIG. 2.

FIG. 3.

FIG. 4.

FIG. 5.

FIG. 6.

FIG. 7.

FIG. 8.

FIG. 9.

FIG. 1 is a front view of a pull incorporating my new design for cabinet hardware.

FIG. 2 is a side view of a pull as seen from the top of FIG. 1.

FIG. 3 is an end view of the pull.

FIG. 4 is an enlarged sectional view taken along the line 4-4 in FIG. 1.

FIG. 5 is an enlarged fragmentary sectional view taken along the line 5-5 in FIG. 1.

FIG. 6 is a front view of an escutcheon plate incorporating my new design for cabinet hardware.

FIG. 7 is a side view as seen from the bottom of FIG. 6.

FIG. 8 is an end view of the plate.

FIG. 9 is an enlarged sectional view taken along the line 9-9 in FIG. 6.

I claim:

The ornamental design for cabinet hardware, as shown and described.
